WEFT-FEEDER FOR WEAVING LOOMS WITH
CONTINUOUS WEFT FEEDING

Raymond Dewas, Amiens, France

Application October 17, 1934, Serial No. 748,657
In France November 10, 1933

1 Claim. (Cl. 139—122)

The invention relates to pirlless shuttles and to weft-feeders belonging to the types which are described particularly in the U. S. applications S. Nos. 673,672, 676,251 and 725,885. It deals with the arrangement of the ends of the said shuttles or weft-feeders in accordance with the U. S. application S. No. 695,996, and it has for its object to prevent the floating or nonfloating warp threads from penetrating into the slot which separates the branches of shuttles, weft-feeders or thread-carriers of the said type.

In the U. S. application S. No. 695,996, several forms of construction have been set forth, of which two amongst others, the second and the third, offer in respect of each of them certain advantages, the combination of which enables the realization of a new form of construction which constitutes in particular the improved weft-feeder forming the object of the invention.

Effectively, the second form of construction described in the said application is characterized by the fact that the groove thereof is arranged obliquely in relation to the middle plane of the shuttle or of the weft-feeder, in such a way that one of its branches has, on the side facing the reed, a height which is approximately equal to half the total height of the said side, so that the point of the beak which prolongs the said branch is approximately at equal distances from the sheets of warp threads and is close to the reed.

Experience has demonstrated that this form of construction offers the advantage of separating the floating threads from the reed at the precise place where the passage, formed by the two divided sheets of the warp, the reed and the point of weaving, affords the maximum opening between the said divided sheets and at the same time the maximum distance from the fell of the cloth, the advantage of this division at the reed increasing in inverse ratio to the travel of the sley and to the degree of opening of the sheets, seeing that the fact must not be lost sight of that frequently it is a question of shuttles of very small dimensions and consequently with reduced shed and with a sley stroke travel which is also reduced.

In the same way the third form of construction described in the said application is characterized by the fact that the end of the branch which terminates in the form of a beak not only has an outer bevelling but also a bevelling on the inner opposite face, the end of the other branch also having outer and inner bevellings.

Experience has demonstrated that this form of construction offers the advantage of protecting the slot particularly well but of dividing the floating threads at a relatively great distance from the reed.

Owing to the combination of the advantages of the forms of construction above referred to,

the new improved form of construction of the weft-inserter which forms the object of the present invention, offers simultaneously the advantage of allowing of the separation of the floating threads at the reed and of ensuring the effective protection of the slot against the introduction of any warp threads, either floating or non-floating, in the event of the shuttle or weft-feeder traversing one of the warp sheets accidentally.

This new form of construction offers moreover, so far as the third form of construction referred to above is concerned, the advantage that having an inclination equal to the weft thread at the time of its presentation, said weft thread penetrates more easily into the slot as the sort of barring up effect resulting from the particular conformation of the ends of the branches at the starting point of the slot need no longer be so pronounced, accordingly, in this new form of construction, the primary point formed by the end of that one of the branches against the reed being prolonged, as in the second form of construction, the warp thread—in the most unfavourable circumstances—passes round this point close to the reed and therefore at a definitely greater distance from the secondary point formed by the end of the other branch, and consequently at a more acute angle in relation to the starting point of the slot.

Finally, this new form of construction offers the advantages:—of allowing of a slighter inclination of the weft thread which, among other things, gives a narrower selvedge; of improving the sliding of the warp threads along the sides of the weft-inserter, and of ensuring a better guiding of the weft-inserter in the shed.

The invention is described hereafter and shown by way of an example in the attached drawing, in which:

Figure 1 is a partial plan view of the pirlless weft-inserter or weft-feeder, before its entry into the shed, at the moment preceding the catching of the weft thread;

Figure 2 is a partial plan view of the opposite side of the weft-inserter as in Figure 1;

Figure 3 is a side view of the weft-inserter, showing the face which is presented to the reed;

Figure 4 is a side view of the back of the weft-inserter showing the face which is presented to the fell of the cloth;

Figure 5 is an end elevation of the extremity of the weft-inserter shown in Figure 3;

Figure 6 being a transverse sectional elevation of Figure 3 on the line AA.

Figure 6a is a plan view of the cutting blade AA.

Figure 6b is a section along the line B—B of Figure 4.

In that which concerns this new form of arrangement of the ends of the shuttles or weft-

feeders, and as in the previous forms of construction, the weft-inserter consists of a body 1 of trapezoidal cross-section of which 2 and 3 are the faces intended to come into contact with 5 the sheets of the warp threads forming the shed, 4 being the small side intended to face the fell of the cloth 6 and 5 the large side intended to face the reed 7.

One of the ends (or, in accordance with circumstances, each of the ends) of this weft-inserter is split for a certain distance at 8 in the direction of its width, so as to divide the body 1 into two branches 9 and 10, the bottom of the slot thus obtained having a cutting blade 11, 10 15 tachable or not, which is intended to cut the weft thread, said cutting blade being arranged on a bias and issuing from a stripping orifice 11' arranged across one of the sides, said orifice at the same time compelling the weft thread to 20 engage with the blade which facilitates the cutting of the thread.

The blade is mounted in the weft-inserter and fixed by a nut 11a in such manner that when the portion 11b of the blade is worn out the blade 25 can be conveniently removed and replaced by a new one. Figure 6a shows the blade in an enlargement of five to one. Figure 6b illustrates the position of the blade 11 in the weft-inserter. The thread 18 is shown as passing around blade 30 11 and as projecting in the form of a loop through the orifice 11'. Due to this arrangement the thread is cut quickly and effectively.

The large side 5 has a wide groove 12 in which is accommodated the weft retaining clamp which 35 can be constituted, either as in the other forms of construction in the U. S. application S. No. 695,996 mentioned above, or in the form of a single branch resting on the opposite side of the groove 12, shaped for this purpose, or again by 40 blocks of springy material fitted with thin metal blades, said clamps being capable of taking one, two or a larger number of weft threads.

In that which concerns the improved arrangement according to the invention of one or of 45 the two ends of the shuttle, for the purpose of keeping off the floating or non-floating threads this arrangement is characterized by the fact that the longer branch 9 is prolonged beyond the shorter branch 10, retaining for a certain 50 distance its width and ending in a cant 13 which extends from the small side 4 to the large side 5 to form the point 14, close to the reed 7, the outer face of this point presenting a trimmed, rounded or bevelled surface 3' merging into the 55 flat face 3 of the body 1 of the weft-inserter, whilst the inner face of the same point offers, as regards the prolonged part of the groove 12, a sloping surface 12' (Figure 5), which, at the junction of the large side 5 with the cant 13, 60 fixes the point 14 approximately half way up the shed, said inclined inner surface 12' being prolonged towards the opposite face 2 in the direction of the small side 4, by means of a surface 13' sloping in the opposite direction which 65 forms an additional thickness 15 intended to cover and protect the slot 8. This additional thickness 15 is in the same plane as the face 2 from which it is separated by the prolongation 8' of the slot 8.

The additional thickness 15 extends to the cant 70 13 by means of a rounded or bevelled surface 15', in order to facilitate, on the one hand, the deflecting of the floating threads and, on the other hand, the easy sliding of the weft thread and its guiding into the slot 8, when it is presented suitably in well known way. The end of 75

the short branch 10 is shaped in almost the same way as in the other forms of construction of the above mentioned U. S. application S. No. 695,996, in the respect that this end has its outer surface trimmed, rounded or bevelled at 2' and merges into the flat surface 2 of the body 1 of the shuttle, the inner surface remaining flat and presenting a small cant 16, starting from the small side 4, to the slot 8, to form a point 17 which is almost at the place where the additional thickness 15 is of maximum width, the edges of the cant 16 and of the point 17 are bevelled, rounded or otherwise shaped with a view to facilitating the passage and the sliding of the weft thread under the point 17 towards the slot 8. 15

It should be understood that, as in the other forms of construction in the above mentioned U. S. application S. No. 695,996 the weft thread 18 is stretched between the point or extremity 6' of the fell of the cloth and the thread guiding eye-let 19 (Figure 1).

The point of presentation can also be advanced beyond the point of the fell of the cloth by means of the device comprising a springy notched blade proposed in the said patent to which the present 25 improvements relate.

The groove, like the slot can of course be sloped differently in relation to the middle plane of the weft-inserter or can be parallel to it, according to the size of the shuttle and the width available 30 and it must be understood that if the groove (and in consequence the slot) is sloped, this is in order to give to the shuttle, with an equal width and depth of groove, particularly reduced dimensions. 35

It is to be understood that alterations, modifications and additions may be made, without departing from the spirit of the invention. For example, in the case of the application of this new form of construction to the ends of the thread carrying needles forming the object of the U. S. 40 application S. No. 725,885 the sheet metal overlap with the triangular notch can be combined with the branches of the conveying needle, so as to contribute to the actual formation of the point, whilst leaving a large opening for the entry of 45 the pulling needle.

What I claim is:

A weft-inserting device comprising a body having two ends, said ends having the shape of two pronged riders, one of the prongs of the rider extending beyond the other whilst retaining the same width, said body having a small side and a large side, said longer prong ending in a cant which extends from said small side to said large side, whereby a point is formed which is adapted to be situated close to the reed and approximately at an equal distance from the sheets, the outer face of said point presenting a trimmed surface joining the plane surface of said body, the inner face of said point presenting an inclined plane surface, said body having another surface which is inclined in the opposite direction and which forms an additional thickness, the first-mentioned inclined plane surface being prolonged to the opposite face in the direction of said small side by the last-mentioned surface, said body having another inclined plane joining the last-mentioned surface to the cant, the shorter prong of said body having a cant beginning at the small side of said body somewhat behind the end of said additional thickness, whereby a point is formed substantially at the place where said additional thickness has its maximum width. 65 70 75
